UNITED STATES PATENT OFFICE

156,214

DESIGN FOR A SCARF

Gladys Emerson Cook, New York, N. Y., assignor to Edgar C. Hyman Co., Inc., New York, N. Y., a corporation of New York

Application February 12, 1949, Serial No. 812

Term of patent 3½ years

(Cl. D3—12)

To all whom it may concern:

Be it known that I, Gladys Emerson Cook, a citizen of the United States of America and a resident of New York, in the county and State of New York, have invented a new, original, and ornamental Design for Scarf, of which the following is a specification, reference being had to the accompanying drawing, forming a part thereof.

Figure 1 is a view showing the left half section of the scarf, and Figure 1a is a view showing the right half section of the scarf, the whole showing my new design.

I claim:

The ornamental design for a scarf, substantially as shown.

GLADYS EMERSON COOK.
